REFRIGERATOR CAR

Garth G. Gilpin, Chicago, Ill., assignor, by mesne assignments, to Standard Railway Equipment Manufacturing Company, a corporation of Delaware

Application June 30, 1943, Serial No. 492,953

7 Claims:

(Cl. 62—17)

This invention relates to refrigerator cars used to transport perishable commodities at a predetermined temperature. The essential features of such a car are an insulated body to retard or prevent ingress of heat during warm weather and egress of heat during cold weather, and a cooling means and a heating means to be used during warm and cold weather respectively.

The invention relates to such refrigerator cars, but particularly to those wherein the cooling means is disposed immediately below the car roof within a cooling chamber separated from the other parts of the car save for an air inlet and an air outlet. The lading is supported below the cooling chamber in spaced relation to the floor by a foraminous floor rack. Flues, preferably associated with the side walls of the car, communicate between the cooling chamber and the space under the floor rack to provide a path for the circulation of air. The path is from the cooling chamber downwardly through the aforementioned flues, through the space under the floor rack, upwardly through the lading compartment thereby cooling the lading, and finally to the cooling compartment, whereupon the cycle is completed.

With the increase in speed of freight trains it has been found that refrigerator cars do not have to be iced so heavily as formerly with the slower moving trains, and thus the number of refrigerant containers may be reduced.

It is an object of my present invention to provide such an overhead bunker type car having fewer refrigerant containers, thereby increasing the economy of refrigerating such cars, as well as reducing the construction cost of such cars.

Another object of the invention is to provide a circulating path for the air so that all the air from the lading compartment is forced to contact the refrigerant.

Other objects and advantages of the invention will appear in the following description thereof.

Referring now to the accompanying drawings forming part of this application and wherein like reference characters indicate like parts:

Fig. 1 is a top plan view, one-half of which is of the roof of a refrigerator car and the other half is of said car with the roof removed and showing in plan the refrigerant tanks and baffles.

Fig. 2 is a section on line 2—2 of Fig. 1.

Fig. 3 is a transverse sectional view of a re-

frigerator car embodying the invention taken through a pair of hatches.

In the form of the invention illustrated one or more refrigerant containers 2 are preferably positioned on each side of the center line of a car adjacent the roof 3 thereof and also preferably adjacent the side walls 4 of the car. Hatchways 5 are provided through the roof 3 above the containers 2 for loading said containers with ice or the like. The hatchways are provided with the usual hatch plug or lid, not shown, for closing the hatchways. Longitudinal partitions 6 extend from end to end of the car, one in spaced relation to each side wall 4, and is secured in position by being attached to spaced vertical posts 7. Metallic, or other suitable sheets 8, having vertical panels 9 pressed therein are also attached to said posts between said posts and said partitions 6, the spaces between the panels 9 and partition 6 forming spaced vertical flues 10 extending from adjacent the top of the car to the bottom thereof. A drip pan 11 is provided immediately below said container 2 but spaced therefrom to form a duct 12 which declines toward and communicates with the upper end of the vertical flue 10. From the inner margin or edge of each of said drip pans 11 there extends upwardly to the car ceiling a partition or member 13, said members 13 being spaced from each other to form a passageway 14 therebetween. Longitudinally spaced transverse carlines extend from side to side of the car and the partitions 13 and drip pans 11 are secured thereto in any desired manner as, for example, by the Z-bars 15. The partitions 13 extend parallel with the side walls of the car slightly beyond the ends of the containers, from which point they are inclined as at 16 to the partition 6, thus enclosing each container. Openings are provided through the partitions 13 of the partitions so that air rising from the lading compartment 17 of the car upwardly through the passageway 14 may pass only through said openings, as indicated by the arrows, Fig. 3, into the duct 12, thence downwardly through the flues 6, to the bottom of the lading compartment.

It is expected that two containers 2 adjacent each end of the car will suffice to provide all the cooling necessary for refrigerated express service. Consequently, all the air rising from the lading compartment will have to pass through the openings 13 in order to be cooled by the refrigerant in the containers, when said air will fan out due to the diverging walls 16,

and pass down distributively through the flues 10. The aggregate area of the flues between each pair of diverging walls 16 approximately equals one-half the area of the passageway 14 so that there will be no slowing up of the air after it enters the duct 12 due to any restriction in size of the flues 10.

A foraminous floor rack 18 is provided, it being spaced from the bottom 19 of the car, leaving the air distributing space 20 therebetween and with which space the flues 10 communicate, so that air descending through said flues enters said space 20, passes upwardly through the foraminous floor and lading compartment, through the passageways 14 into the ducts 12 and repeats the cycle.

To assist the air in fanning out distributively to the side flues, shorter diverging baffles 21 may be provided for such purpose.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. An air cooling system for a railway car having a plurality of vertical flues in one of said walls, and a lading compartment, said system comprising a refrigerant container above the lading compartment and adjacent one of said walls, a structure partially surrounding the container forming an air cooling chamber having an air inlet communicating with said lading compartment, an air outlet communicating with said flues, said inlet being at a higher elevation than said outlet for convective air circulation, the ends of said structure diverging from adjacent said inlet to said side wall flues so that circulating air is discharged into the flues adjacent the container and also flues beyond the container.

2. An air cooling system for a railway car having a roof, a hatch in said roof, spaced carlines supported by opposite walls of the car, a plurality of vertical flues in one of said walls, and a lading compartment, said system comprising a refrigerant container supported by said carlines below the hatch and adjacent one of said walls, a structure partially surrounding the container forming an air cooling chamber having an air inlet communicating with said lading compartment, an air outlet communicating with said flues, said inlet being at a higher elevation than said outlet for convective air circulation, the ends of said structure diverging from adjacent said intake to said side wall flues so that circulating air is discharged into the flues adjacent the container and also flues beyond the container.

3. An air cooling system for a railway car having a roof, a hatch in said roof, spaced carlines supported by opposite walls of the car, a plurality of vertical flues in one of said walls, and a lading compartment, said system comprising a refrigerant container supported by said carlines below the hatch and adjacent one of said walls, a structure partially surrounding the container forming an air cooling chamber having an air inlet communicating with said lading compartment, an air outlet communicating with said flues, said inlet being at a higher elevation than said outlet for convective air circulation, the ends of said structure diverging from adjacent said intake to said side wall flues so that circulating air is discharged into the flues adjacent the container and also flues beyond the container.

erant container supported by said carlines below the hatch and adjacent one of said walls, a structure partially surrounding the container forming an air cooling chamber having an air inlet communicating with said lading compartment, an air outlet communicating with said flues, said inlet being at a higher elevation than said outlet for convective air circulation, the ends of said structure diverging from adjacent said intake to said side wall flues so that circulating air is discharged into the flues adjacent the container and also flues beyond the container, and partitions within said air cooling chamber to direct some of said circulating air into the flues adjacent the container and other portions of said air into the flues remote from the container.

4. A structure as defined in claim 3 wherein said ends and said partitions are positioned to substantially equally proportion said intakes and said outlets.

5. In combination with the roof and walls of a refrigerator car; a refrigerant container in the upper part of the car, means providing an air flue associated with a wall of said car, an enclosing structure for said container forming an air cooling chamber thereabout, said chamber having an air inlet communicating with the interior of said car, an air outlet communicating with said flue means, the ends of said structure diverging from the ends of said inlet to the ends of said outlet.

6. In combination with the roof and walls of a refrigerator car; spaced refrigerant containers in the upper part of the car, flue means associated with a wall of said car, an enclosing structure for said containers forming an air cooling chamber thereabout and comprising a bottom and spaced apart ends extending from said bottom to the car roof, said chamber having an air inlet adjacent one side of said container communicating with the interior of said car, an air outlet adjacent the other side of said container communicating with said flue means, the ends of said structure diverging from the ends of said inlet to the ends of said outlet.

7. In combination with the roof and walls of a refrigerator car; longitudinally spaced refrigerant containers in the upper part of said car, flue means associated with a wall of said car, an enclosing structure for said containers forming an air cooling chamber thereabout and comprising a bottom and spaced apart ends extending from said bottom to the car roof, said chamber having an air inlet adjacent one side of said container of approximately the same length as said container and communicating with the interior of said car, an air outlet adjacent the other side of said container extending beyond the ends of said container and communicating with said flue means, the ends of said structure diverging from the ends of said inlet to the ends of said outlet, said outlets being contiguous at said flue means.

GARTH G. GILPIN.
